Carl M. Sinclair

UNITED STATES PATENT OFFICE.

JOHN BERGMAN, OF DES MOINES, IOWA.

GASOLENE-STOVE SHIELD ATTACHMENT.

1,273,317.

Specification of Letters Patent. Patented July 23, 1918.

Application filed September 21, 1917. Serial No. 192,620.

To all whom it may concern:

Be it known that I, JOHN BERGMAN, a citizen of the United States, and resident of Des Moines, Polk county, Iowa, have invented a new and useful Gasolene-Stove Shield Attachment, of which the following is a specification.

The object of this invention is to provide an improved shield attachment adapted to 10 isolate and protect the gasoline supply tank of a gasoline stove relative to the burners and flame.

A further object of this invention is to increase the safety to users and premises in 15 which a gasoline stove is used, by protecting and shielding the supply tank, which may be subject to leakage, relative to open flames on the burners.

A further object of this invention is to 20 provide improved means for mounting a shield attachment on a stove.

A further object of this invention is to provide improved means for adjusting the height of the shield attachment and adapting 25 it for use with stoves having supply pipes of different lengths whereby the supply tanks are located at various altitudes.

A further object of this invention is to 30 provide means for steadyng and equilibrating the attachment and the feed pipe relative to one another.

My invention consists in the construction, arrangement and combination of elements hereinafter set forth, pointed out in my 35 claims and illustrated by the accompanying drawing, in which—

Figure 1 is a side elevation showing a gasoline stove with my improved shield attachment in position for practical use. 40 Fig. 2 is an end elevation of the same, dotted lines indicating an adjusted position of the attachment. Fig. 3 is an enlarged detail horizontal section illustrating the means employed for maintaining the adjustment of 45 the two members of the attachment. Fig. 4 is an enlarged detail vertical section illustrating the means employed for securing the attachment to a stove.

The device as shown consists essentially 50 of two sections, a lower or attaching section and an upper or protecting section vertically adjustable on the lower section, said sections being designated respectively by the numerals 10 and 11. The sections 10, 11 preferably 55 are formed of sheet metal of suitable weight finished in any desired manner, the lower

section being plane substantially throughout its height and the upper section being plane in its lower portion. The sections 10 11 are formed with marginal flanges 12, 13 at right angles to their bodies, the flanges 12 of the lower section being recurved and embracing, and forming vertical slide bearings for the flanges 13 of the upper section, as shown in Fig. 3. One of the flanges 13 of the upper section is formed with a vertical slot 14 and a screw 15 passes loosely through a socket 16 carried on the outer face of the adjacent flange 12 and also loosely through said slot and is adapted to be seated at its threaded 60 inner end in a nut 17 or threaded bearing carried by the inner face of said flange 12. By this means the upper section 11 may be adjusted and secured vertically relative to the lower section 10. 75

The lower section 10 is provided with means for attaching the device to the top of a gasoline stove, such as 18, such stoves commonly being formed with an outwardly and downwardly inclined marginal flange 19 80 around their tops. A flange 20 is formed on or a flanged member is fixed to and transversely of the lower margin of the lower section 10, on the inner side thereof relative to the stove, and is adapted to rest on the plane 85 upper surface of the top, as across one end thereof, where the supply tank is located at the end of the stove as shown. Attaching clips 21 are laid against the outer face of the lower section 10 and are formed with vertical slots 22 adapted to receive bolts 23 passing through the lower portion of said section and adapted to receive wing-nuts 24 90 on their ends, by which the clips may be vertically adjusted on the section. Hooks 25 95 are integrally formed on the lower ends of the clips 21 and are inclined to correspond to the inclination of the flange 19 of the stove top, and are adapted to engage over and around the lower margins of said flange. 100 The nuts 24 may be loosened to permit downward movement of the clips, after which the device is placed in position on the stove top, the clips are drawn upwardly so that the hooks 25 engage beneath the flange 105 19 of the stove top, and the nuts 24 are tightened, thereby clamping the margin of the top between the hooks 25 and the flange 20, so that the device is held in upright position on said top. 110

The upper portion of the upper section 11 is curved or offset to form a bay 26 directed

toward the stove 18, and said bay is adapted to accommodate a gasolene supply tank such as 27 carried by a feed pipe 28 above the stove and adapted to supply gasolene there-
5 through to the burners of the stove at times. A loop 29 or other suitable stay member is attached to the section 11, preferably adjacent the lower portion of the bay 26, and a tie 30, as of wire, is secured to said loop and
10 adapted to be engaged with the upper end portion of the feed pipe 28, whereby the feed pipe and supply tank are secured relative to the attachment, and both the tank and the attachment are steadied and equilibrated.
15 The shield serves to protect and isolate the supply tank relative to open flames on the burners of the stove, and in case any leakage occurs in the tank or feed pipe, the fumes or fluid therefrom is prevented from coming
20 in contact with the flames, thereby preventing explosions and increasing safety to the user and the premises.

I claim as my invention—

1. In a gasolene stove having a burner and
25 a fuel-supply tank spaced from said burner and at greater altitude than the top of the stove, a shield attachment comprising a device adapted to be mounted in vertical position on and rise from the stove top between
30 said burner and supply-tank, whereby said tank is isolated from said burner.

2. In a gasolene stove having a burner and a fuel-supply tank spaced from said burner and at a greater altitude than the top of the
35 stove, an attachment comprising a shield formed of members vertically adjustable relative to each other and adapted to be mounted transversely of and extend substantially at right angles above the stove
40 top between the supply tank and burner.

3. In a gasolene stove having a burner and a fuel-supply tank spaced from said burner and at a greater altitude than the top of the stove, a shield attachment comprising a body
45 portion adapted to be mounted in vertical position on and across the stove top and extending upwardly therefrom between the tank and burner, and means for securing said body portion to the stove top.

50 4. A gasolene-stove shield attachment,

comprising a body portion formed in two sections, means for adjusting the upper section vertically on the lower section, and means for securing the lower section to a stove top.

5. In a gasolene-stove having a burner and fuel-supply tank, a shield attachment, comprising a body portion, and means for attaching said body portion to and transversely of the top of said stove adjacent the supply tank and between said tank and the burner, said body portion being formed with a generally plane lower portion and with a swell or bay in its upper portion to accommodate said tank.

6. A gasolene-stove shield attachment, comprising a body portion formed of two sections, each of said sections being formed with marginal flanges, the flanges of one section embracing and forming slide bearings for the flanges of the other section, means for securing one section relative to the other, and means for securing the lower section to a stove.

7. A gasolene-stove attachment, comprising a shield formed with a horizontal flange adapted to rest on a stove top, and clips vertically slidable and adjustable on said shield and formed with downwardly projecting hooks adapted to engage beneath said stove top.

8. A gasolene-stove attachment, comprising a shield formed with a horizontal flange adapted to rest on a stove top, bolts extending through said shield, and clips formed with vertical slots through which said bolts project, said clips being formed with downwardly projecting hooked members adapted to engage beneath said stove top.

9. An attachment for a gasolene stove having an elevated supply tank supported by a feed pipe, comprising a shield, means for securing said shield in vertical position on and transversely of a stove top adjacent the supply tank of said stove, said shield being formed with a swell or bay adapted to accommodate the supply tank, and means for securing the upper portion of said shield to the support for said supply tank.

JOHN BERGMAN.
